ECHO TORPEDO DETONATOR

John Hays Hammond, Jr., Gloucester, Mass.

Application November 28, 1932, Serial No. 644,613

22 Claims. (Cl. 114—21)

This invention relates to the detonation of explosives, and more particularly to the exploding of a torpedo as it passes beneath a ship.

The invention provides a mechanism whereby 5 a series of high frequency compressional waves are emitted from a torpedo and impressed upon the surrounding medium. When these waves are reflected from a solid object such as the bottom of an enemy ship, they are picked up by suitable 10 microphones located on the torpedo, and cause the detonation of the explosive charge of the torpedo.

The invention also consists in certain new and 15 original features of construction and combination of parts hereinafter set forth and claimed.

Although the novel features which are believed 20 to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which:

25 Figure 1 represents diagrammatically the forward part of a torpedo provided with this invention.

Figure 2 illustrates diagrammatically a modified form of the invention showing control of the 30 horizontal rudders.

Like reference characters denote like parts in the several figures of the drawings.

In the following description and in the claims, 35 parts will be identified by specific names for convenience, but they are intended to be as generic in their application to similar parts as the art will permit.

Referring to the accompanying drawings, and more particularly to Fig. 1, there is shown a 40 water borne body, such as a carrier of explosives, having a water tight torpedo hull 10, and arranged to be propelled in the usual manner (as by propellers 8 and 9 located at the after end, shown in Fig. 2). The hull 10 is provided with 45 two transverse bulkheads 11 and 12, thus providing two compartments 13 and 14, the former being filled with an explosive charge, such as TNT.

A hole is provided in the hull 10 at the top 50 of the compartment 14. This hole is closed by a diaphragm 15 which is operatively connected to an oscillator or receiver 16, which may be of any desired form. A suitable oscillator is shown and described in the patent to Lawther No. 1,518,- 55 123, issued December 2, 1924. This oscillator is

operated by means of a super-audible frequency producing vacuum tube circuit 17, controlled by two contacts 18 and 19. These contacts engage a commutator 21, which is driven by a clock-work mechanism 22 which may be wound as by 5 a key 23.

The receiver or oscillator 16 transmits compressional waves of super-audible frequency into the water for a purpose hereinafter described more in detail.

For automatically starting this mechanism, a heavy weight 24 is secured to the end of a flat spring 25, the upper end of which is fastened to the casing of the clock mechanism 22. The weight 24 is provided with a projection 26, which normally engages a finger 27, which controls the starting of the clockwork mechanism. Engaging the end of the finger 27 is a spring 28 which is supported on a bracket 29. When the weight is moved out of engagement with the finger 27, 20 as by the sudden starting of the torpedo, the spring 28 forces the finger 27 inwardly, thus starting the clock mechanism operating.

The commutator 21 is made of insulating material and is provided with three segments of conducting material 31. Engaging the commutator 21 are two contacts 32 and 33 which at suitable times close the circuit from an electrical microphone or receiver 34 to vacuum tube detector 35. The pick-up 34 may be of any desired form, such 30 for example, as that shown at 105 in Fig. 20 of the patent to Dorsey No. 1,625,245, issued April 19, 1927.

The detector 35 may be of any desired construction, the output circuit of which is connected 35 to a relay 36. This relay controls the circuit to a detonator 37 located in the explosive charge in the compartment 13.

The microphone 34 has a diaphragm similar to diaphragm 15 of receiver 16, which closes a similar opening in the side of the hull 10.

In the operation of this system, when the torpedo is fired, the inertia of the weight 24 causes it to be moved backward relative to the torpedo, thus disengaging the projection 26 from the finger 45 27 which is moved upwardly under the action of the spring 28. This causes the clockwork mechanism 22 to start turning the commutator 21 at a predetermined speed. When the contacts 18 and 19 are on a conducting segment 31, it will 50 cause the generator of super-audible frequency 17, to generate a current of high frequency, such for example, 20,000 cycles per second, which is impressed upon the diaphragm 15, thus generating a series of compressional waves in the water 55

above the torpedo. This will continue until the commutator 21 has rotated sufficiently to break the circuit between the contacts 18 and 19, thus causing the oscillator 16 to cease producing high frequency waves.

The train of high frequency waves produced by the receiver 16 travels upwardly through the water above the torpedo, and if they should strike the under surface of the hull of a vessel 10 above the torpedo, they will reflect or "echo" back through the water and be received by the electrical microphone 34. This will cause small currents to be generated in the winding of this microphone of the same frequency as that produced by the receiver 16. These currents will be detected or rectified by the detector 35, and direct current pulsations caused to pass through the winding of the relay 36, thus energizing this relay, which closes the circuit through the detonator 37, thus exploding the charge in the compartment 13 when the torpedo is directly beneath the enemy ship.

It is thus seen that in this system, as soon as the torpedo is fired, short impulses of high frequency compressional waves will be emitted from the diaphragm 15. These waves will not directly affect the microphone 34, however, as the circuit of this receiver is open during the time these waves are being produced. When the torpedo 30 passes beneath an enemy ship, the high frequency waves will be reflected from the hull of this ship, and will be received by the microphone 34. The time of reception of these waves is determined by the distance the torpedo is below 35 the hull of the enemy and by the speed of travel of the sound through the water. As the torpedo passes underneath the ship, the distance between torpedo and ship will be such that the pulses will be received at a time when the contacts 32 40 and 33 are engaged by one of the conducting segments 31. In this way, in case the torpedo misses a direct hit with the ship and passes beneath it as it often does in actual warfare, it will be caused to explode directly beneath the 45 ship, thus producing as much damage as though a direct hit were made.

In the modified form of the invention shown in Fig. 2, the contact of the relay 36 is connected to a solenoid 41, located in the after-body of the 50 torpedo, instead of to the detonator of 31. The core of this solenoid normally engages a valve 42 which is mounted for reciprocation in a valve casing 43, which forms part of the end of a cylinder 44. This cylinder communicates with 55 the interior of the valve by means of a port 45. Also communicating with the interior of the valve is a pipe 46, which is supplied with fluid under pressure from any suitable source, not shown. Slidably mounted in the cylinder 44 is a piston 60 47, which is operatively connected to an arm 48, which is pivoted by rotation to the shell of the torpedo at 49.

The torpedo is provided with the usual vertical and horizontal rudders 51 and 52. The latter are 65 operated by means of a link 53 from the horizontal steering engine 54, which is supplied with fluid under pressure from a pipe 55 and is controlled by a valve 56 operated in a well known manner from the depth mechanism 57. Secured 70 to the link 53 is a collar 58 which is located in the path of travel of the arm 48.

In the operation of the modified form of the invention shown in Fig. 2, the torpedo after being fired is maintained at a predetermined depth by 75 the usual depth control mechanism 57 and hori-

zontal steering engine 54. When the torpedo passes beneath an enemy's ship, the operation is the same as that described in connection with Fig. 1, causing the energization of the relay 36, which closes the circuit through the solenoid 41. 5 This causes the core of this solenoid to be moved to the right thus releasing the valve 42, which is moved upwardly under the action of the springs surrounding this valve, thus allowing fluid under pressure to pass from the pipe 46 through the 10 port 45 to the interior of the cylinder 44. This causes the piston 47 to be moved to the left, thus rotating the arm 48 in a counterclockwise direction. This arm engages the collar 58 and forces it together with a link 53 to the left, against the 15 action of the steering engine 54, thus throwing the horizontal rudders 52 into the hard up position, which causes the torpedo to be steered sharply upward and against the bottom of the 20 hull of the enemy vessel where the war head of the torpedo is exploded on contact with the hull in the usual manner.

Although only a few of the various forms in which this invention may be embodied have been shown herein, it is to be understood that the invention is not limited to any specific construction, but might be embodied in various forms without departing from the spirit of the invention or the scope of the appended claims.

What is claimed is:

1. In a self propelled body carrying an explosive charge, means for producing compressional waves, means for receiving said compressional waves after reflection from an object, and means operable in response to said received waves for 35 causing the explosion of said charge.

2. In combination with a self propelled body, means for producing a series of short sound impulses, means for receiving said sound impulses after reflection from the hull of a ship, and 40 means operable in response to said sound impulses for causing the detonation of an explosive charge carried by said self propelled body.

3. In combination with a torpedo having a warhead, a sound producer carried on the upper 45 surface of said torpedo, a sound receiver located adjacent thereto, means for causing said sound producer to emit a series of short impulses, and means operated by said sound receiver for causing the explosion of said warhead when said sound 50 impulses are received after reflection from the under surface of a vessel.

4. In a self propelled vessel, means associated therewith for transmitting compressional waves to a surrounding medium comprising a vibratory 55 diaphragm and a space discharge device associated therewith and adapted to vibrate said diaphragm at a definite predetermined frequency, an electro-magnetic receiving device located on the upper side of said vessel and adapted to receive compressional waves reflected from a distant object, a space discharge device associated with said receiving device, means whereby said devices are caused to respond to said frequency, 60 and means operated by said receiving device for causing the detonation of an explosive charge carried by said vessel.

5. In a torpedo, an electrical oscillator located on the upper surface thereof and adapted to 70 transmit compressional waves to the surrounding medium, a receiving device located on the upper surface of said torpedo for receiving said compressional waves after reflection from an object, 75 and means operated by the energization of said

receiving device for causing the explosion of said torpedo.

6. In combination with a self propelled body carrying an explosive charge, means for producing superaudible sound vibrations in the medium surrounding said body, means for receiving said sound vibrations, means for alternately making operable said transmitting and said receiving means and means controlled by said receiving means for detonating said explosive charge.

7. In a torpedo, means for producing compressional waves, means for receiving said compressional waves after reflection from a distant object, and means operable on the reception of said waves for causing the detonation of the explosive charge of said torpedo.

8. In a torpedo, means for producing compressional waves, means for receiving said compressional waves after reflection from a distant object, means operable on the reception of said reflected waves for causing the detonation of the explosive charge of said torpedo, and means for preventing said detonation by the direct action of said waves.

9. In combination with a self propelled body, means for producing compressional waves, means for receiving said compressional waves after reflection from an object, and means operable in response to said reflected compressional waves for causing the body to be directed upwardly.

10. In combination with a torpedo having a warhead, a sound producer carried on the upper surface of said torpedo, a sound receiver located adjacent thereto, means for causing said sound producer to emit a series of short impulses, and means operated by said sound receiver for causing said torpedo to be steered upwardly when said sound impulses are received after reflection from the under surface of a vessel.

11. The method of exploding a torpedo which includes producing sound waves on said torpedo receiving said sound waves after reflection from an object and causing said sound waves to explode said torpedo.

12. In a torpedo, an electrical oscillator located on the upper surface thereof and adapted to transmit compressional waves to the surrounding medium, a receiving device located on the upper surface of said torpedo for receiving said compressional waves after reflection from the under side of a vessel, and means operated by the energization of said receiving device for causing the horizontal rudders of said torpedo to be rotated upwardly.

13. In combination with a self propelled body, means for producing super-audible sound vibrations in the medium surrounding said body, means for receiving said sound vibrations, means for alternately making operable said transmitting and said receiving means, and means controlled by said receiving means for causing said torpedo to be steered in an upward direction.

14. In a self propelled body carrying an explosive charge, means for producing compressional waves traveling in a vertical direction, means for receiving said compressional waves after reflection from the under side of an object, and

means operable in response to said received waves for causing the explosion of said charge.

15. In a torpedo, means for producing compressional waves of a definite frequency, means for receiving said compressional waves after reflection from a distant object, and means responsive to said frequency and operable on the reception of said waves for causing the detonation of the explosive charge of said torpedo.

16. In a torpedo, means for producing compressional waves, means for receiving said compressional waves after reflection from a distant object, means operable on the reception of said reflected waves for causing the detonation of the explosive charge of said torpedo, and a timing device for controlling the operativeness of said last mentioned means so that it can not be operated by direct waves.

17. In a torpedo, means for producing and propagating oscillatory energy, a device for receiving said energy after reflection from a surface in the vicinity of said torpedo and means to steer said torpedo upwardly responsive to said device.

18. In a torpedo having a war head, means for producing and radiating energy, means for receiving said energy after reflection from an outside object, and means responsive to the received energy to detonate said war head.

19. In a torpedo having a war head, means for producing and propagating compressional vibrations above the audible frequency range, a device for receiving said vibrations after reflection thereof from an external surface and means responsive to said device for detonating said war head.

20. In an explosive carrier, means causing said carrier to travel through the water at a depth below the bottom of an enemy ship, a transmitter for transmitting impulses, a receiver for receiving said impulses, and means whereby said receiver is operable for impulses modified by the target only when said carrier has reached a point beneath the bottom of said ship.

21. In combination, a torpedo, means for causing said torpedo to run at a depth below the bottom of an enemy ship such that no part of the torpedo physically engages the ship, a transmitter on said torpedo for transmitting energy through the water, a receiver on said torpedo for receiving said energy, and torpedo control means actuated by said receiver in response to a change in such energy produced by the influence of the ship when the torpedo has reached a point beneath the bottom of the ship.

22. In combination, a torpedo, means for causing said torpedo to run at a depth below the bottom of an enemy ship such that no part of the torpedo physically engages the ship, a transmitter on said torpedo for transmitting energy through the water, a receiver on said torpedo for receiving said energy after reflection from an external surface, and torpedo control means actuated by said receiver in response to a change in such energy produced by the influence of the ship when the torpedo has reached a point beneath the bottom of the ship.

JOHN HAYS HAMMOND, JR.
